United States Patent Office

Des. 181,308
Patented Oct. 29, 1957

181,308

EARRING

Helen Neszpaul, Pittsburgh, Pa.

Application January 17, 1955, Serial No. 34,006

Term of patent 7 years

(Cl. D45—9)

Fig. 2.

Fig. 1.

Fig. 1 is a side elevational view of an earring showing my new design; and Fig. 2 is a front elevational view thereof.

I claim:

The ornamental design for an earring substantially as shown.
